JOHN L. WAGNER AND JAMES SEATH, OF TERRE HAUTE, IND., ASSIGNORS TO THEMSELVES, THOMPKINS A. LEWIS, OF INDIANAPOLIS, IND., HENRY R. DUVALL, OF NEW YORK, N.Y., AND ROBERT S. COX, OF TERRE HAUTE, IND.

CAR-DOOR.

SPECIFICATION forming part of Letters Patent No. 280,537, dated July 3, 1883.

Application filed May 21, 1883. (No model.)

To all whom it may concern:

Be it known that we, JOHN L. WAGNER and JAMES SEATH, of the city of Terre Haute, county of Vigo, and State of Indiana, have invented certain new and useful Improvements in Car-Doors, of which the following is a specification.

Our said invention consists in the combination, with car-doors, of certain mechanism whereby such doors are adapted to slide along beside the car, as usual, and to be closed in flush with the car-sides, as will be hereinafter more particularly set forth.

Referring to the accompanying drawings, which are made a part hereof, and on which similar letters of reference indicate similar parts, Figure 1 is a side elevation of a car provided with a door embodying our invention, one door being open and the other closed, the open door being shown by dotted lines; Fig. 2, a horizontal sectional view, looking downwardly from the dotted line *z z*; Fig. 3, a vertical sectional view, looking to the right from the dotted line *y y*; Fig. 4, an enlarged detail view similar to a portion of Fig. 3; Fig. 5, a view similar to Fig. 4, except that the shaft is turned in the other direction; and Fig. 6, a perspective view of substantially the parts shown by Fig. 4.

In said drawings, the portions marked A represent the body of the car, B the door, and C the crank-rod by which said door is operated.

The car-body A is substantially of the usual construction. It has rabbeded jambs *a a'*, similar to those usually provided for a hinged swinging door, which receive the door B in such a manner that when said door is fully closed the outer surface thereof is flush with the outside of the car-body, as shown. It is also provided with the slides A', which are similar in every respect to the usual slides upon which ordinary car-doors are mounted, except that they turn inwardly as they approach the front edge of the door-opening, as shown most plainly in Fig. 2.

The door B is a car-door of ordinary construction, and is mounted upon the slides A', as shown. Two of its bearings, *b b'*, are of the ordinary form, and are attached rigidly to the

door, while the other two, *c c'*, are only connected to the door through the crank-rod C.

The rod C is secured to the door B by bearings *b'*. It has short cranks *c'* upon its ends, upon which are the bearings *c*. It is also provided with a handle or lever, C', which is firmly secured thereto. This handle, when turned around against the door, turns the rod C, so that the cranks *c'* project inwardly, carrying the bearings *c* and the door toward the car, and forcing said door into the rabbeded jamb, as shown. When said handle is forced around in the other direction, the cranks *c'* draw the bearings *c* and the door B outwardly, freeing said door from the jambs, and permitting it to be moved along the slides A', and thus opened. When the handle C' is swung around against the door, it preferably engages with a staple, *b²*, and is adapted to be secured thereto by a pin or hasp, *b³*, or a lock. A like staple, *a²*, and said pin *b³* may be used to fasten the door open, if desired.

The operation of our said invention may be recapitulated as follows: The door being open and it being desired to close it, said door is moved along the slides A' by pulling on the handle *b'* until the front edge comes in contact with the jamb *a*. The handle C' is then turned around until it rests against the door B, carrying with it the rod C, which, through the cranks *c'* on the ends thereof and the bearings *c* on said cranks, forces the back edge of the door tightly into contact with the jamb *a'*, and thus completes the closing of the door into the rabbedes of said jambs as completely as though said door were hung on hinges, like an ordinary swinging door, instead of on slides, as is essential in this class of cars. The advantages of having the doors closed into the jambs flush with the outside of the cars are that when so closed no water or sparks of fire can get into the cars, which is a common source of much loss and damage when ordinary car-doors are used.

It will be understood that there may be a rod C at each edge of the door instead of at one edge only, in which case the bars A' would run straight instead of being curved at the end next the front edge of the door.

Having thus fully described our said invention, what we claim as new, and desire to secure by Letters Patent, is—

1. The combination, with a car, of a door mounted on slides, and provided with a crank-rod connected with bearings therefor, whereby when said rod is turned in one direction said door will be forced into its jambs, and when turned in the other direction said door will be drawn outwardly therefrom, substantially as set forth.
2. The combination of a car, a sliding door therefor, slides on which said door is mounted, a crank-rod mounted on said door, bearings mounted on the cranks of said rod, which rest on said slides and support the door, and means for operating said rod, whereby said door is moved into or withdrawn from its jambs, substantially as set forth.
3. The combination of the car A, the slides A', curved inwardly at the front edge of the

door, the car-door B, having bearings *b b*, the crank-rod C, having bearings *c c* upon its cranks, and a handle for turning the same, substantially as shown and described, and for 25 the purposes specified.

4. The combination, with a car, of a door mounted on slides, one edge of which is supported by bearings attached directly to the door, and the other edge of which is supported through a crank-rod by bearings upon the ends of said crank-rod, substantially as set forth.

In witness whereof we have hereunto set our hands and seals, at Indianapolis, Indiana, 35 this 19th day of May, A. D. 1883.
